DESIGN FOR A BABY'S BED

J. Russell Kuhn, Oklahoma City, Okla.

Application July 8, 1936, Serial No. 63,715

Term of patent 14 years

To all whom it may concern:

Be it known that I, J. Russell Kuhn, a citizen of the United States of America, residing at Oklahoma City, county of Oklahoma, State of Oklahoma, have invented a new, original, and ornamental Design for a Baby's Bed, of which the following is a specification, reference being had to the accompanying drawing, wherein:

The figure is a perspective view of a baby's bed, showing my new design.

The opposite end of the bed is identical to the end clearly illustrated in the accompanying drawing; whereas the opposite side is plain and is without the drawer and door features as shown in the side of the bed illustrated in the drawing.

I claim:—

The ornamental design for a baby's bed, as shown and described.

J. RUSSELL KUHN.
